Patented Feb. 27, 1968

210,342

MOTORSCOOTER

Ernest D. Smith, 448 Blue Ridge Drive,
Martinez, Calif. 94553

Filed Oct. 4, 1966, Ser. No. 4,157

Term of patent 14 years

(Cl. D90—8)

FIG. 5

FIGURE 1 is a left side elevation view of the motor-scooter;

FIGURE 2 is a right side elevation view of the motor-scooter;

FIGURE 3 is a front elevation view of the motor-scooter;

FIGURE 4 is a rear elevation view of the motor-scooter; and

FIGURE 5 is a perspective view of the motor-scooter.

I claim:

The ornamental design for a motor-scooter, as shown.
